UNITED STATES PATENT OFFICE.

MARY M. NEWKIRK, OF INDIANAPOLIS, INDIANA.

SEED GRADING AND CLEANING MACHINE.

1,323,784.

Specification of Letters Patent.

Patented Dec. 2, 1919.

Application filed October 14, 1918. Serial No. 258,015.

To all whom it may concern:

Be it known that I, MARY M. NEWKIRK, a citizen of the United States, and a resident of Indianapolis, county of Marion, and 5 State of Indiana, have invented a certain new and useful Seed Grading and Cleaning Machine; and I do hereby declare that the following is a full, clear, and exact description thereof, reference being had to the accompanying drawings, in which like numerals refer to like parts.

This invention relates to seed grading and cleaning machines, and particularly to that class adapted to be used for cleaning and 15 grading wheat, oats, beans, clover seed and the like.

One feature of the invention is the provision of a plurality of screens arranged to form a hurdle so arranged that different 20 kinds of seed will be separated and graded while passing over the hurdle.

A further feature of the invention is the provision of means for causing the grains to assume a horizontal position before passing 25 onto the perforated portion of the top screen.

A further feature of the invention is the provision of means for imparting an oscillating movement to parts of the screen 30 structures in the cleaning machine, and at the same time deliver a jar thereto, whereby any particles of grain tending to stick in the mesh of the screen will be loosened and caused to descend into the proper receptacle or compartment.

Other objects and advantages will be hereinafter more fully set forth and pointed out in the accompanying specification.

In the accompanying drawings which are 40 made a part of this application Figure 1 is a perspective view of the seed grading and cleaning machine, showing the means thereon for imparting a blow as well as give longitudinal movement to certain parts of the 45 grading screens of the machine. Fig. 2 is a fragmentary side elevation of the bar for delivering a blow to one of the grading screens. Fig. 3 is a sectional view thereof as seen on line 3—3 Fig. 2. Fig. 4 is a detail elevation of a bar employed for imparting motion to the blow delivery part. Fig. 5 is a vertical sectional view through the machine showing the machine having a hurdle construction therein. Fig. 6 is a top

plan view of the hurdle construction removed from the machine. Fig. 7 is a sectional view thereof as shown on line 7—7 Fig. 6 and Fig. 8 is a fragmentary elevation, on an enlarged scale, of one of the hurdle screens.

Referring to the drawings in which similar reference numerals designate corresponding parts throughout the several views, 1 indicates the frame of the machine, 2 a grain receiving hopper, 3 a fan housing 65 and 4 a shaker frame supported and operated by a conventional suspending means common to devices of this class and as all of said parts are of the usual construction it is not deemed necessary to show the same, 70 they forming no part of the present invention. In addition to the usual screens carried by the shaker frame for cleaning and separating the grain, grading screens 5 and 6 are provided, which are positioned below 75 the shaker frame, and preferably disposed at an inclination, said screens being slidably mounted between the posts of the frame 1. In order to impart oscillatory movement to said screens 5 and 6, a shaker bar 7 is 80 provided, which extends through a clip 8, attached to the frame 1, said bar having a plurality of openings 9 in its length for the reception of a pin 10, so that the stroke of the bar 7 may be varied. The lower end of the shaker bar is enlarged or increased in width, preferably by bending the bar edgewise upon itself, the enlarged portion 11 being pivotally attached to a side bar 12 of the grading screen 6, while the upper 85 end of the upwardly bent portion 13 of the bar 7 is provided with a slot 14, in which fits a rod 15 extending through the side bar 16 of the grading screen 5.

To more readily adapt the enlarged portion 11 for engagement with the grading screens 5 and 6, as said screens extend at an angle, the enlarged portion is preferably extended at an angle to the main portion of the shaker bar 7 as best shown in Fig. 2 of the drawings, although it will be noted that said enlarged portion may be extended in a straight line with the remaining portion of the shaker bar, if desired. The shaker bar 7 is rocked back and forth on the pivot pin 95 10 by pivotally attaching an operating bar 17 to the upper end of the bar 7, the opposite end of said operating bar having an 100 105

opening 18 therein, in which fits a cam 19 fixed to a fan shaft 20, and as said cam is mounted eccentrically on the fan shaft, the operating bar 17 will be given a longitudinal movement as the fan shaft rotates. This imparts an oscillatory or longitudinal movement to the screens 5 and 6, while a vibratory movement is imparted thereto from a portion of the shaker frame 4 as 10 is usual in devices of this kind.

In addition to the above movements of the grading screen 5, it is desirable to jar or deliver a blow to said screen, so as to cause vertical vibration of the screen 21, 15 so that should any grains stick in the mesh the blow delivered to the screen will loosen same, and to this end the enlarged portion 11 of the bar 7 is provided with an angular portion 22, which extends under the side bar 16 of the grading screen 5, and as said bar 7 swings on its pivot 10 the edge of the angular portion 22 will strike the edge of the side bar 16 and deliver a slight jar thereto. As it is necessary to frequently 20 remove the screen 5, the slot 14 is open at its upper end, so that the rod 15 carried by the grading screen 5 can be readily engaged with or disengaged therefrom.

Mounted within the shaker frame 4 is a 30 hurdle 23, comprising a frame 24 in which are mounted screens 25, 26 and 27, which, being preferably constructed of sheets of metal, have a plurality of circular perforations 28 therethrough for the passage of the 35 grain or seed. The prime feature of this construction is to separate oats from wheat, although it may be used for many other purposes with the same success. In view of the fact that the oats grain is of considerable length and the wheat grain is shorter and more plump, the oats grain, when descending from the hopper 2, usually 40 descends lengthwise or vertically, and consequently would be far more liable to pass directly through the perforations 28, but in order to obviate this objectionable feature, and to cause the oats grain to rest lengthwise on the top screen, the inner end portion 29 of the upper screen 25 is made 45 imperforate, consequently the oats grain, when striking this portion of the screen, and which is situated directly under the opening in the hopper, will assume a position horizontal of the screen and pass on 50 to the perforated portion in this position, and consequently the oats grain will ride over the perforations and leave the upper screen 25 at the outer end thereof, while the shorter wheat grains will descend 55 through said perforations. After the grain passes through the screen 25 it is further separated and graded by the screens 26 and 60 27, and as the screens are of different lengths the grain passing over each screen 65 will be deposited in a separate place thereby

keeping the various grades of grain separated.

The invention claimed is:

1. A seed grading and cleaning machine, including a grain grading screen, an 70 oblong vertically extending shaker bar, a pivot for said bar between its ends, means for removably and pivotally attaching the screen to the lower portion of said bar, means for swinging said bar on its pivot for 75 imparting longitudinal movement to said screen, and an offset portion on said bar extending below the edge of said screen for delivering a blow to the lower edge of the screen, when the bar is rocked on its pivot. 80

2. A seed grading and cleaning machine, including a stationary frame, a vertically extending shaker bar pivoted at a point between its ends to said frame, a pair of grading screens at the lower end of said bar, one above the other, means to pivotally attach the lower screen to said bar, means for removably and pivotally attaching said upper screen to the bar, means for rocking the shaker bar back and forth on its pivot for 85 imparting longitudinal oscillatory movement to said screen, and a laterally bent portion on the bar for delivering a blow to the upper screen when the bar is moved in either direction. 90

3. In a seed grading and cleaning machine, the combination with a fan structure and a grading screen, of a flat adjustable and pivotally mounted shaker bar, said bar having an enlarged portion at its lower end, 100 formed by bending the lower end portion of the bar edgewise and extending the upwardly bent portion along the edge of the bar, said enlarged portion having an offset portion extending below said grading screen, and means operated by the fan structure for rocking said shaker bar on its pivot whereby the offset extension on the bar will deliver a blow to said grading screen. 110

4. In a seed grading and cleaning machine, the combination with a frame, and a mesh grading screen removably mounted in said frame, of a vertically extending shaker bar, means for adjustably and pivotally attaching said bar to parts of the frame of the screen, means to removably and pivotally attach said grading screen to the lower portion of said shaker bar, means to rock said shaker bar on its pivot, 115 and means on the shaker bar for imparting a blow to said grading screen when the bar is rocked on its pivot. 120

5. In a seed grading and cleaning machine, the combination with a pivotally mounted shaker bar, having its lower end bent upwardly and edgewise to the bar, the upwardly bent portion having an elongated slot in its free end, of a grading screen and a rod projecting from the side bar of the 130

grading machine adapted to enter said slot for pivotally engaging the screen with the shaker bar.

6. In a seed grading and cleaning machine, the combination with a frame and a pair of grading screens, one above the other and longitudinally movable in said frame, of a vertically extending shaker bar pivoted to said frame, means to pivot the lower 10 grading screen to the lower end of the

shaker bar, and a rod projecting from the upper grading screen, parts of said shaker bar having an elongated slot for the reception of said rod whereby the upper screen will be removably pivoted to said shaker bar.

In witness whereof, I have hereunto affixed my signature.

MARY M. NEWKIRK.
